TRICYCLE HANDLE-BAR OR SIMILAR ARTICLE

Clifford Brooks Stevens, Milwaukee, Wis., assignor to Junior Toy Corporation, a corporation of Delaware

Application February 13, 1956, Serial No. 40,152

Term of patent 14 years

(Cl. D34—15)

Fig. 1 is a top plan view of a tricycle handle-bar or similar article, showing my new design;

Fig. 2 is a front elevational view thereof;

Fig. 3 is a perspective view thereof; and

Fig. 4 is a side elevational view thereof.

I claim:

The ornamental design for a tricycle handle-bar or similar article, as shown.
